UNITED STATES PATENT OFFICE.

GERRIT V. ORTON, OF SAN FRANCISCO, CALIFORNIA, ASSIGNOR TO HIMSELF, HENRY P. GREGORY, AND SILAS W. GREGORY, OF SAME PLACE.

PLANING-MACHINE.

SPECIFICATION forming part of Letters Patent No. 331,730, dated December 1, 1885.

Application filed August 12, 1885. Serial No. 174,191. (No model.)

To all whom it may concern:

Be it known that I, GERRIT V. ORTON, a citizen of the United States, residing at San Francisco, in the county of San Francisco and State of California, have invented certain new and useful Improvements in Planing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention consists of a planing-machine in which the cutter-head is driven by a belt on each end and arranged to be vertically adjustable with the upper feed-rolls, said upper feed-rolls being driven by a belt and train of 20 gears upon one side of the machine, while the lower feed-rolls are driven by a belt and train of gears upon the other side, the object being to dispense with expansion-gearing and allow the use of lighter trains of gears.

25 The invention also consists in certain details of construction, as hereinafter set forth. In the annexed drawings, illustrating my invention, Figure 1 is a side elevation of a planing and matching machine provided with my 30 improvements. Fig. 2 is a vertical longitudinal section of the same. Fig. 3 is a plan view of the machine, showing the matcher-heads and guides; and Fig. 4 is a sectional end elevation of the machine.

35 Like letters refer to like parts in the several views.

The frame A of the machine supports the bed B and the journal-boxes of the lower feed-rolls, C C. The upper feed-rolls, D D, cutter-head E, and their usual accompaniments are carried by an adjustable frame, F, capable of a vertical movement by which said upper rolls and cutter-head are raised and lowered together to correspond to the thickness of the 45 stuff to be planed. The frame F on each side has a depending inclined guide-arm, G, that is adjustably supported in the inclined guide-ways H H on the side of the machine. At the lower end of each guide-arm G is a cross-head or bearing for a vertically-inclined screw-shaft, I, which carries at its lower end a gear,

J, that meshes with a pinion, K, on a transverse shaft, L. This shaft may be fitted at one end with a crank-handle or formed for attachment of a wrench, by which the necessary adjustment of the cutter-head and upper rolls can be effected through the frame F and intermediate connections. 55

The cutter-head E is driven by belts *a a*, one on each end, from pulleys M M on a shaft, 60 *b*, at the entrance end of the machine.

The upper feed-rolls, D D, are driven by a belt, *c*, Fig. 1, from a small pulley, *d*, Fig. 3, on one end of the shaft *b* to a pulley, *e*, Figs. 1 and 4, on a stud at the side of the 65 machine. This pulley *e* carries a pinion, *f*, meshing with a gear-wheel, *g*, having a pinion, *h*, that actuates another pinion, *i*, on a stud, and which in turn moves a gear, *k*, that actuates an intermediate double gear, *m*, for 70 driving the gears *n n* of the front and back upper feed-rolls. This intermediate double gear, *m*, revolves upon an annular bush, *p*, Fig. 3, which in turn is fitted to the outer end of one of the cutter-head mandrel-bearings, 75 thus affording a perfect bearing for said gear without interfering with the attachment of a pulley to that end of the cutter-head mandrel.

The upper and lower rolls being driven independent of each other, some such arrangement as that above described becomes essential, as the centers of the cutter-head and upper rolls are nearly in the same plane; and to get a driving-pulley upon both ends of the 80 cutter-head its mandrel must pass through the intermediate gear at or near its center. Where expansion gearing is used to connect the upper and lower rolls, the under rolls drive the upper ones, and the expansion-trains are arranged one in front of the cutter-head mandrel and the other back, so that in such cases there is no difficulty in providing for the pulleys upon both ends of the cutter-head. In my 85 machine, however, as the upper and lower rolls are driven independently and without expansion-gear trains, the intermediate gear for actuating the front and back upper feed-rolls must center at or near the center of the cutter-head mandrel, and therefore cannot be made 90 to run upon a stud. 95

On the opposite side of the machine, Fig. 3,

upon the shaft *b*, is a small pulley, *d'*, that is connected by a belt, *c'*, Figs. 1 and 2, to a large pulley, *e*, that is geared to drive the lower feed-rolls. The pulley *e* carries a pinion, *f'*, 5 that drives a gear-wheel, *g'*, having a pinion, *h'*, for actuating the gear *s* of the front lower feed-roll, which gear *s* in turn actuates an intermediate gear, *t*, for driving the gear *v* of the back lower roll.

10 The gearing for driving the upper and lower sets of feed-rolls independent of each other is shown in Fig. 4, and the position of the several gears is shown by broken lines in Figs. 1 and 2, the gears for driving the upper rolls 15 being indicated by lines broken at long intervals, while the gears for driving the lower rolls are indicated by lines broken at short intervals. By thus driving the upper and lower rolls independently upon opposite sides of the 20 machine I am enabled to dispense entirely with expansion-gearing, and can employ to advantage lighter trains of gears than usual.

The roll-belts *c c'* are tightened or slackened to start or stop the feed by means of two tighteners, *N N*, attached to arms *O O*, that are 25 adjustably mounted on a cross-shaft, *w*, by means of set-screws *y y*, so as to permit adjustment of each tightener to the state of its own belt. Both tighteners are manipulated 30 at the same time by a lever, *P*, attached to the shaft *w*, and having a spring-locking pawl for engagement with a rack, *Q*, by which the tighteners are held in contact with or away from the belts.

35 On the shaft *b* are pulleys *z z*, that carry belts *R R*, for actuating the matcher-heads *S S*, which, together with their usual accompaniments, may be arranged near the delivery end of the machine. These matcher-heads 40 are adjustably supported in the ordinary manner, as shown in Fig. 4.

When the machine is to be used for tonguing and grooving or matching lumber, and for similar purposes, matcher-guides *T T* will be 45 arranged adjustably upon the bed *B*, as shown in Fig. 3.

It will be observed that the pulley *e*, with 50 its pinion *f*, and the connected gearing for actuating the intermediate gear, *m*, and upper roll-gears, *n n*, are all mounted in one of the

arms *G* of the frame *F*, so as to be adjustable therewith.

By arranging the upper and lower rolls to be driven by belting and gearing independently from opposite sides of the machine I 55 am enabled to provide for the necessary vertical adjustment of the cutter-head and upper rolls without employing expansion-gear trains and owing to the peculiar way of gearing the front and back upper roll-gears by means of 60 a double intermediate gear having a bearing on one of the cutter-head mandrel-boxes I can at the same time drive the cutter-head by belting at both ends. This arrangement results in giving a very strong, positive, and 65 durable feed, which is operated by a single tightening-lever, as before explained, and enables the cutter-head to be rotated smoothly and with great power.

What I claim as my invention, and desire to 70 secure by Letters Patent, is—

1. In a planing-machine having upper and lower feed-rolls driven independently by a belt and gearing on opposite sides of the machine, the combination, with the front and 75 back upper roll-gears, *n n*, of an intermediate gear, *m*, arranged to rotate upon an annular bushing, *p*, fitted to the outer end of one of the cutter-head mandrel-bearings, whereby the cutter-head mandrel is enabled to carry a pulley at each end, substantially as described.

2. In a planing-machine, the combination of the main frame *A*, having inclined guide-ways *H H* on each side, the lower feed-rolls, *C C*, mounted in journal-boxes supported in 85 said main frame, the vertically-adjustable frame *F*, having guide-arms *G G*, the vertically-inclined screw-shafts *I I*, having gears *J J*, the transverse shaft *L*, having pinions *K K*, the cutter-head *E*, and upper feed-rolls, *D D*, mounted in said adjustable frame *F*, and 90 belting and gearing on opposite sides of the machine for driving the upper and lower feed-rolls independently, substantially as described.

In testimony whereof I affix my signature in 95 presence of two witnesses.

GERRIT V. ORTON.
